UNITED STATES PATENT OFFICE.

THOMAS G. ADAMS, OF NEW HAVEN, CONNECTICUT.

DESIGN FOR A MATCH-SAFE.

SPECIFICATION forming part of Design No. 20,952, dated July 21, 1891.

Application filed February 13, 1891. Serial No. 381,524. Term of patent 3½ years.

To all whom it may concern:

Be it known that I, THOMAS GOVE ADAMS, a citizen of the United States, residing at New Haven, in the county of New Haven and State of Connecticut, have invented a new and useful Design for a Match-Safe Souvenir of Chicago's Fair, of which the following is a specification.

The design for which a patent is solicited is a match-safe, consisting in the representation of the lower limbs of the human figure with hollow openings, as shown in the drawing. In front and centrally placed between the said members is a sphere, and both these

elements rest on a cylindrical base, the said base having a beveled edge and a bead on the same plane as the top.

What I claim, and desire to secure by Letters Patent, is—

The design for a match-box, as herein shown and described.

In testimony whereof I have hereunto set my hand in presence of two subscribing witnesses.

THOMAS G. ADAMS.

Witnesses:

THOMAS D. ADAMS,
